(57) **CLAIM**

The ornamental design for an LED lens, as shown and described.

DESCRIPTION

FIG. 1 is a perspective view of an LED lens showing our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top side elevational view thereof.

FIG. 7 is a bottom side elevational view thereof.

FIG. 8 is a cross-sectional view thereof; and,

FIG. 9 is an exploded view thereof.

The broken lines in the Figures are for illustrative purposes only and form no part of the claimed design.
